STAND FOR CALORIMETRIC BOMBS

Filed Aug. 31, 1926

Fig. 1.

FIG. 2

UNITED STATES PATENT OFFICE.

JAMES DARROCH, OF BARRHEAD, SCOTLAND.

STAND FOR CALORIMETRIC BOMBS.

Application filed August 31, 1926, Serial No. 132,383, and in Great Britain March 30, 1926.

My invention relates to improvements in and connected with the stands for calorimetric bombs, and has for its object to provide one of a simple and efficient nature.

5 According to this invention, the stand is formed of three or any suitable number of arms of any suitable metal, the end of each of which is turned up forming as it were a kind of casing, in which the bomb sits and 10 slightly bent outwards at the extreme ends thereof. Suitably attached to each arm or integral therewith there is a depending leg by which the stand rests on the bottom of the tank or container, the upper ends of said legs 15 act as a support for the bottom of the bomb. A pin slightly shorter than the legs so that it cannot come into contact with the bottom of the bomb is suitably attached to the centre of the bottom of the inside of the tank or container, the end of the pin passes through a 20 hole or opening formed in the centre of the base of the stand thereby fixing the position of the stand centrally in the bottom of the tank or container.

25 In order that my invention may be properly understood and readily carried into effect, I have hereunto appended one sheet of drawings, of which

Figure 1 is a sectional elevation showing 30 the stand in situ in the tank or container and with the bomb placed on said stand.

Figure 2 is a plan of Figure 1 with bomb removed.

Referring to the drawings, A^1 , A^2 , A^3 , are 35 the arms of which the stand A is formed, and B^1 , B^2 , and B^3 are the bent-up portions which, as shown in Figure 1, are turned outwards at the upper end to admit of the bomb C being more readily placed in the stand. The depending legs D^1 , D^2 and D^3 are screwed or 40 otherwise suitably attached to the arms A^1 , A^2 and A^3 of the stand A . D^1 , D^2 and D^3 are the lower portions of the legs resting on the bottom of the tank or container E , while the 45 upper portions, as stated, project through the stand A in order to facilitate the free cir-

culation of water underneath the bomb C which rests upon them instead of on the arms. The pin F is screwed or otherwise suitably fixed to the centre of the bottom of inside of 50 the tank or container E , the upper end of which pin F engages with the stand A by passing through the hole or opening F' in the center of the stand A , thus ensuring that the latter and consequently the bomb shall 55 always be placed centrally in the calorimeter, a condition which is essential for accurate results.

From my improvements it will be obvious 60 that contact of the stirrer with the bomb cannot occur as sometimes happens with other types of stand since with them the bomb is placed in what in the judgment of the operator only is the central position. If the bomb is wrongly placed it is necessary for the operator to adjust it which is a waste of time.

Time is also saved in adjusting the position of the bomb in the calorimeter, since the form is always put down in exactly the right place, consequently the operator need not 70 waste time trying the stirrer or otherwise to discover whether the bomb is properly placed.

A freer circulation of water under the bottom of the bomb is permitted which is an important consideration since it is conducive 75 to accuracy of results and my improvements are also suitable for use with any type of bomb or stirrer.

Claim:

Apparatus of the class described comprising 80 a tank having an upstanding centrally arranged pin in the bottom and a stand comprising radial arms united together at their inner ends and having at their point of union an opening for the reception of said pin, said 85 arms having vertically arranged upwardly extending outer end portions, said stand also having depending legs secured to the said arms and bearing on the bottom of said tank.

In witness whereof I affix my signature.

JAMES DARROCH.
